UNITED STATES PATENT OFFICE

GEORGE W. OSBORN, OF CLEVELAND, OHIO

GAUGE LIGHT

Application filed February 15, 1926. Serial No. 88,334.

The objects of the invention are to provide means for illuminating the water gauge or column of a steam boiler, in such a manner that the rays of light will be confined thereto and will not be spread about the boiler room. The device fills a long felt want since boilers are often placed in the darkest corner of the boiler room where the water level in the gauge is difficult to read, and an explosion may result if the water level becomes too low in the boiler.

To accomplish these objects, an electric lighting bulb is enclosed within a metal casing which is provided with a narrow vertical front opening through which the rays of light are projected upon the full length of the water gauge, and the walls of this slot prevent the rays from scattering about the boiler room.

20 Also a concave reflector is formed in the cover of the casing by means of which the rays are definitely projected upon the gauge.

The invention also includes a casing having a narrow elongated slot in its front wall, 25 means within the casing for attaching an electric lamp bulb, the said casing being provided with an opening in its rear wall through which the lamp can readily be inserted or removed, and a cover therefor detachably hinged thereto as its lower end and an automatically locking fastener at the upper end which, when released, permits the cover to drop below the lower end of the opening in the casing, and when the cover is closed automatically locks the same in closed position.

35 It also includes a cover provided with a concave reflector in its inner surface which may be polished or may be coated with aluminum paint or other illuminating coating, or the cover may be constructed of a white or light colored metal such as aluminum.

The invention further includes the details of construction and combination and arrangement of parts hereinafter described illustrated in the accompanying drawings and specifically pointed out in the claims.

In the accompanying drawings, Fig. 1 is a vertical section of the device, Fig. 2 is a 40 front elevation thereof and Fig. 3 is a rear

elevation thereof, Figure 4 is a plan of Figure 1.

In these views A represents an elongated hollow casing provided with a lamp socket or connection B for the lamp bulb C which hangs vertically in the casing.

45 In the front wall of the casing a narrow vertical slot D is formed which is as long as the tube of the water gauge, R, so as to permit the illumination of the entire length of the gauge. Over this opening a heavy plate of glass E is attached by means of the rectangular frame F and screws G. A packing H behind the glass prevents the same from breaking.

50 The rear wall of the casing is open at I to permit ready access to the lamp bulb and a cover J for the opening is provided with a hook shaped hinge eye K which can be inserted in the depending loop L at the lower end of the casing, thus forming a detachable hinged connection therewith. This enables the cover to drop automatically away from the opening when released so as to uncover the full opening leading to the lamp. When closed the cover is locked in place by means of the metal loop or keeper M pivoted at N to the sides of the casing, which falls automatically over the upper end of the cover when it is elevated into place.

55 A notch O adjacent to the upper end of the cover is engaged with the inner side of the loop at P when the cover is closed, thus preventing the locking loop from being accidentally displaced.

60 In the inner face of the cover is formed a concave mirror surface Q which will reflect and concentrate the rays of the lamp upon the gauge tube R adjacent thereto and the walls of the narrow slot will prevent the rays from diverging. If the cover is constructed of a bright metal such as aluminum it may not be necessary to polish the surface of the mirror, or the metal surface may be coated with aluminum paint or illuminating substance. Also the bottom face of the cover is inclined at S to reflect the rays from the lamp upon the water in the lower part of the gauge.

65 In Fig. 4 the vertical sides of the casing are shown to be inclined toward the vertical

sides of the narrow vertical aperture or slot in the front wall of the casing thus enabling them to reflect the lateral rays of the lamp through said aperture.

⁵ In this manner all the inner surfaces of the casing are employed to increase the illuminating power of the lamp and to direct the rays through the narrow aperture so that they will not be wasted upon surrounding objects.

¹⁰ Having described the invention what I claim as new and desire to secure by Letters Patent is:

¹⁵ 1. In an illuminating device for a water gauge tube, the combination with a vertical gauge tube of a lamp and a vertically elongated casing therefor, said casing being provided with a vertical elongated slot in its front wall and a glass thereover parallel with ²⁰ said gauge tube, the back wall of said casing being provided with a concave mirror opposite to said lamp, and opposite to the normal water level in said tube, and also provided with a vertical back wall and with vertical ²⁵ oblique side walls arranged to deflect the light of said lamp through said slot upon said tube, the bottom of said casing being inclined obliquely to the back wall to prevent the downward dispersion of the rays of light.

³⁰ 2. In an illuminating device for a water gauge the combination with a vertical gauge tube of a lamp and a vertically elongated casing spaced therefrom, said casing being provided with a vertical elongated slot in its ³⁵ front wall, and with a glass thereover parallel with said gauge tube, the back wall of said casing being provided with a concave mirror opposite to said lamp, and opposite to the normal water level in said tube, and also provided with a vertical back wall and with oblique side walls arranged to deflect the light of said lamp through said slot upon said tube, the bottom of said casing being inclined obliquely to the back wall to prevent the downward dispersion of the rays of light, said rear ⁴⁰ wall being hinged to the casing at the bottom and opening downwardly to a lower level than said casing—to permit of ready access to said lamp.

⁴⁵ 30 In testimony whereof, I hereunto set my hand this 13th day of November, 1925.

GEORGE W. OSBORN.
